UNITED STATES PATENT OFFICE.

AMOS MALLORY, OF MYSTIC BRIDGE, CONNECTICUT.

FLOAT-DETECTING MECHANISM FOR LOOMS.

SPECIFICATION forming part of Letters Patent No. 331,897, dated December 8, 1885.

Application filed February 16, 1884. Serial No. 120,975. (No model.)

To all whom it may concern:

Be it known that I, AMOS MALLORY, a citizen of the United States, residing at Mystic Bridge, in the county of New London and State of Connecticut, have invented a new and useful Improvement in Float-Detecting Mechanism for Looms, of which the following is a specification, reference being had to the accompanying drawings.

10 Figure 1 is a plan view of a loom embodying my improvements. Fig. 2 is a vertical section taken on the line xx in Fig. 1. Fig. 3 is a vertical section taken on the line yy in Fig. 1; and Fig. 4 is a vertical section on the line zz in Fig. 1, showing the position of the comb and its attendant mechanism when the loom is thrown out of gear. Fig. 5 is a detail view.

This invention has relation to looms; and it consists in the novel construction and arrangement of parts constituting a stop-motion for throwing the loom out of operation when a float occurs in the warp, as will be hereinafter fully described, and particularly pointed out in the claims appended.

25 A serious trouble met with in the operation of all looms, in weaving the various kinds of cloth to which they are adapted, is the formation of floats in the cloth—that is to say, if a thread breaks in the warp it will kink up back 30 of the lathe and hold the threads of the shed together, and causes the shuttle, instead of passing properly through the shed, to pass over or under the wrong threads of the tangled warp, thereby producing floats, or imperfect 35 places in the cloth.

My object is to prevent the formation of floats in the cloth, and the accompanying illustration, hereinafter described, shows my means for accomplishing the result.

40 Referring by letter to the accompanying drawings, A designates the frame of the loom, A' the lathe of the loom, and B a comb. The lathe A' is operated by the crank-shaft J, connected to the lathe-arms by rods in the usual 45 manner, as shown. The shipper-handle K, by which the loom is started and stopped automatically, is also of the ordinary construction, and when automatically shifted, as hereinafter explained, throws the driving-belt onto the 50 idler-pulley and stops the loom motion, as usual.

The lower bar, B', of the lathe A' is provided near each end with bearing-arms CC, consisting of horizontal rearwardly-extending arms provided each with a vertical fork, c, the arms 55 of which are beveled on their inner upper edges, and having each a vertical perforation, d. The ends of the comb-shaft e rest in the forks c c of these bearing-arms, the portions f, resting therein, being made rectangular in 60 form, in order that the comb may not turn while its shaft rests or remains below the bevels g of the forks. Near the inner faces of the forks c c, depending arms h h are hung to the comb-shaft e, said arms being passed down 65 through the vertical perforations d of the bearing-arms C C, being encircled by spiral springs i i, and being provided with shoes E E at their lower ends. The spiral springs i i have their bearings against the lower faces of 70 the bearing-arms C C and the upper faces of the shoes E E, and normally hold the ends of the comb-shaft in the bases of the forks c c.

F designates a cam-shaft having bearings in the lathe-arms below the comb-shaft. The 75 cams k k are located directly under the shoes E E on the depending arms h h. Near one end this shaft F is provided with a ratchet-wheel, H, fixed to said shaft and engaging a spring-pawl, l, on the bearing-plate m, secured 80 to the lathe-arm at that end of the loom.

To the under face of the upper rail, n, of the loom-frame is secured a bearing, o, provided with a pivoted feed-pawl, p, one end of which rests loosely in a lug, p', the other end 85 being arranged to engage the ratchet-wheel H on the shaft F, after passing through a forked guide, p''. To the back of the comb B is secured a depending angle-arm, Q, the inclination of the angle being toward the front of the 90 loom. To the under face of the breast-beam r of the loom-frame is pivoted a lever, L, which extends beyond the right-hand end of the loom-frame, and is intended to engage the shipper-handle K at the proper time to release 95 it from its notch and permit it to shift the driving-belt onto the idler to stop the loom. This shipper-handle is operated by a spring, K', in the ordinary manner.

At each revolution of the shaft J the shuttle 100 passes through the shed, and the ratchet-wheel on the cam-shaft F is turned one notch by the

- feed-pawl. The revolutions of the shaft J or pick are continued until the cams *kk* come in contact with the shoes E E on the depending arms *hh* and push the comb up into the warp.
- 5 If there is no entanglement of the threads of the warp, the teeth of the comb will pass forward with the lay through the warps without meeting with resistance, and the comb will drop back to its original position in the forks *cc*. If, however, there are threads broken, which tangle in and hold the threads of the shed together as the harnesses are worked, and thereby cause a float in the cloth, the comb B, in passing forward through the warp, will 15 come in contact with the snarl and will be turned back in the upper portions of the forks *cc*, which operation will raise the angle-arm Q, connected to the back of the comb B, to such a position that when the lathe comes forward the angle-arm Q will strike the pivoted lever L, which acts on the shipper-handle K, thereby releasing the shipper-handle K and throwing the belt onto the idle-pulley, thus stopping the loom to permit the warp to be mended.
- 20 25 The devices are very simple in their construction and operation, do not add materially to the cost of the loom, and indicate positively when a float is about to be formed in the cloth, thereby rendering it possible to prevent such 30 formations.

Having thus fully described my invention,

what I claim as new, and desire to secure by Letters Patent of the United States, is—

1. The combination of the lathe having the bearing-arms C C, provided with the vertical arms, with the comb having its shaft provided with rectangular portions near its ends, and thereby adapted to be received between the vertical arms of the bearing-arms C C, the angle-arm Q, the cam-shaft F, having the cams 40 and the ratchet-wheel, the holding-pawl engaging with the ratchet-wheel, the depending arms *h*, hung to the comb-shaft, and having the bearing-springs *i*, the feed-pawl, tripping-lever, and shipper-handle, substantially as 45 described.

2. The combination of the lathe having the bearing-arms CC, with the pivoted comb having the depending arms hung to its shaft, bearing-springs for said arms, and the angle-arm secured to the back of the comb, the lever L and shipper-handle, the cam-shaft having the cams and the ratchet-wheel, the holding-pawl, and the feed-pawl for moving the ratchet-wheel, substantially as described. 55

In testimony that I claim the foregoing as my own I have hereto affixed my signature in presence of two witnesses.

AMOS MALLORY.
